UNITED STATES PATENT OFFICE.

ANSLEY H. FOX, OF PHILADELPHIA, PENNSYLVANIA, ASSIGNOR TO ANSLEY H. FOX CO.,
A CORPORATION OF DELAWARE.

GAS-OPERATED MACHINE-GUN.

1,293,396.

Specification of Letters Patent.

Patented Feb. 4, 1919.

Application filed May 26, 1916. Serial No. 99,953.

To all whom it may concern:

Be it known that I, ANSLEY H. FOX, a citizen of the United States, residing at Philadelphia, in the county of Philadelphia and

5 State of Pennsylvania, have invented certain new and useful Improvements in Gas-Operated Machine-Guns, of which the following is a specification.

10 My invention relates to breech-loading gas-actuated guns, and more particularly to gas-actuated automatic machine guns.

15 The prime object of this invention is to so construct a gas-actuated machine gun as to furnish a maximum of efficiency with a minimum of operating parts.

20 A further object of the invention is the simplification and strengthening of the mechanism of a gas-operated automatic machine gun, by which the certainty and reliability of its operation is assured and the various processes of manufacture are made easier and more economical.

25 Another object of the invention is to provide improved air-cooling means for cooling the barrel of the gun, in connection with the gas-actuated and power-controlling parts of the gun.

30 A still further object of this invention is to furnish improved cartridge-feeding devices for retaining and releasing the cartridges and maintaining a continuous automatic firing of the gun. And finally, the object is to provide certain details of construction in connection with the ejector mechanism of the gun.

35 The foregoing and such other objects as may appear from the ensuing description are attained by the novel features of construction, combination, and arrangement of parts, 40 hereinafter fully described, illustrated in the accompanying drawings, and particularly pointed out in the claims appended hereto, it being understood that slight changes in the form, proportion, and minor 45 details of the construction may be resorted to without departing from the spirit or sacrificing any of the advantages of the invention.

45 In the accompanying drawings it will be seen that:

Figure 1, is a longitudinal sectional view of the improved mechanism embodying my invention showing the gun mechanism in the ready to fire position.

50 Fig. 2, is a longitudinal sectional view showing the mechanism in the act of firing.

Fig. 3, is an enlarged central transverse sectional view of the cartridge magazine showing cartridges radially positioned therein.

60 Fig. 4, is a vertical sectional view of the cartridge magazine, taken on the line *a—a*, Fig. 3.

Fig. 5, is an enlarged sectional elevation through a portion of the cartridge magazine and gun, taken on the line *b—b*, Fig. 1.

65 Fig. 6, is an enlarged plan view of the sliding breech-bolt showing the cartridge blank ejecting and extracting mechanism in connection therewith.

Fig. 7, is an enlarged sectional elevation, taken on the line *c—c*, Fig. 1.

70 Fig. 8, is an enlarged sectional elevation, taken on the line *d—d*, Fig. 1, and

Fig. 9, is an enlarged sectional elevation, taken on the line *e—e*, Fig. 2.

75 Similar numerals of reference are employed to designate corresponding parts throughout the several figures of the drawings.

80 In the embodiment of this invention as illustrated and which shows a preferred construction, the numeral 1 indicates the gun-barrel and 2 is the gun frame or receiver, to which the gun-barrel is rigidly secured by screw-threads shown at 3, in Figs. 1 and 2. The gun frame or receiver is provided with a longitudinal chamber 4, in line with the bore of the gun-barrel, within which the breech-block and controlling mechanism reciprocates.

85 Figs. 1, 2 and 3 illustrate my improved means for air-cooling the gun barrel, which consists of a cylindrical air jacket composed of two sections 5 and 6, each section being open at both ends, the rear section 5 being connected at one end to the gun frame 2, and at the other end to a ring 7, secured to the gun-barrel near the forward end portion of the barrel, said rear section having a series of openings or ports 8 at its rear end to freely admit the air which is drawn over and around the barrel and through the air jacket by the suction created at its forward end caused by the forward rush of powder gases leaving the muzzle of the gun-barrel which barrel is somewhat shorter than the surrounding air jacket, as shown. The forward section 6 of the air jacket extends from the ring 7 to a point beyond the muzzle of the gun, its forward end being screwed into

the said ring 7 at the point 9. A sleeve also composed of two sections 10 and 11, each section being provided with a series of radially projecting ribs 12, which extend longitudinally, is shown surrounding the gun-barrel and the air as it passes through the air jacket and between the series of ribs carries off the heat as it is drawn therethrough. The rear ribbed sleeve section 10 is firmly held between the forward end of the gun frame or receiver and the rear face of the ring 7, while the forward sleeve section 11 is held between the said ring 7 and the muzzle, said forward section forming the mouth-piece of the gun-barrel by being screwed onto the barrel at the muzzle end, as shown. If desired, these ribs 12 may be milled on the barrel and left integral therewith instead of using a separate ribbed sleeve.

The said ring 7 is slid over the muzzle and held in place by the forward sleeve section 11, constituting the mouth-piece, which forces the ring rearward against the shoulder 13 formed on the gun-barrel, and the ring is prevented from turning by a key 14, carried by the gun-barrel and which engages a key-slot formed in said ring, and an opening 15 is provided on either side of the vertical center of the ring to permit the free passage of air therethrough, as clearly shown in Fig. 7.

By thus securely fastening the ring 7 to the gun-barrel at the point registering with the gas outlet port 16 formed in the gun-barrel, the gas is caused to pass from said port 16 through the vertically disposed opening 17, and the lateral opening 18, formed within the ring, thus conveying the escaping gas from the port 16 in the barrel, to the head of the gas operated piston 19, and said ring 7 is so formed as to carry the forward end of the tube or casing 20; a screw 20' for regulating the size of the opening leading to said piston, and the front gun sight 21.

The tube or casing 20 is secured at its rear end to the forward end portion of the gun frame or receiver 2, and is provided intermediate its length with a gas outlet port 23, and a piston 19 and a piston rod 22 is adapted to reciprocate within said casing, the said piston rod being surrounded by a helical spring 24, the rear end of the spring resting in contact with the forward end of the gun frame or receiver, and its forward end resting against the rear face of the piston 19.

The numeral 25 indicates the action slide 60 adapted to reciprocate back and forth within the gun frame or receiver, said slide being fastened at its front end portion by a pin 26, or in any other suitable manner, to the rear end portion of the piston rod 22, and 65 provided with an upwardly projecting lug

27 at its rear portion; a longitudinally extending slot 28 which passes transversely therethrough forming an upper cam surface 29 and a lower cam surface 29'; a notch or recess 30, which is milled into the bottom 70 thereof, and adapted to engage the projecting end portion 31 of a trigger 32 pivotally secured to the bottom portion of the gun frame or receiver. The said action slide is also provided at its upper portion with a 75 shouldered portion 32'; a longitudinal recess or groove 33, within which is pivoted a spring actuated pawl 34 having an upward extending lug 35 at one end thereof, and an intermediate upward projecting lug 36 having front cam surfaces 36', and within a recess formed in the action slide beneath the sear is seated a coiled spring 37 adapted to force the pawl in an upward direction.

Projecting rearwardly within the gun 85 frame or receiver is a solid integral portion 38, its upper surface forming a support for the breech-bolt 29, its lower surface forming a guide for the upper surface of the action bolt, and its rear lower corner 38' 90 being rounded for the purpose hereinafter referred to.

The reciprocating breech-bolt 39 is provided with an integral downward extending lug 40 at its rear end portion, and a central 95 longitudinal opening therethrough adapted to receive a firing pin 41, a portion of the pin being surrounded by a helical spring 42 adapted to keep it out of contact with the cartridge until the gun operating parts 100 assume their proper firing position, and said pin is provided with a recessed portion 43 and a securing pin 43' is fitted in said recess in order to retain the firing pin in its proper relative position. Pivoted to the forward 105 end of the breech-bolt is a shell extractor 44, actuated by the helical spring 45 in the usual manner as shown in Fig. 6, and the rear end portion of the breech-bolt is cut-away at each side thereof to form locking 110 shoulders 46. Milled or cut in one side of the breech bolt is a longitudinal recess or groove 47 forming a shouldered portion 48 near its forward end portion, adapted to operate a shell ejector 49, which is pivoted to the receiver or frame, since by reference to Fig. 6 of the drawings it will be readily seen that by the forward movement of the breech-bolt the front end of said bolt will contact with the inclined portion 50 of 115 the ejector pushing the ejector out of the forward path of the bolt and causing the rear end portion 51 of the ejector to enter the longitudinal groove or recess 47 formed lengthwise in the side of the bolt, hence during the last part of the rearward movement of the breech bolt the shouldered portion 48 will strike against the rear end 51 of the ejector and throw the forward end against the side of the empty shell with sufficient 120 125 130

force to eject it out of the gun through the ejection slot 48' milled in the side of the frame or receiver. The ejector remains in this position, as shown in Figs. 1 and 6, as the next loaded shell comes down from the magazine thus serving as a rest or platform for the loaded cartridge and preventing it from rolling out of the ejector slot 48' until the breech-bolt starts to move forward when the front of the bolt will push the cartridge forward so the bullet end of the shell enters the cartridge chamber in the barrel just before the front end of the bolt will push the ejector out of the path of the breech bolt, 10 Fitted loosely within the longitudinal slot 28, in the action slide 25, is a cylindrical pin 52 extending transversely therethrough each end of said pin carrying upwardly extending locking arms or bars 53, said arms 20 or bars 53 being adapted to lock and unlock the breech bolt by the forward and rearward movement of the action slide, since when the action slide, which is attached to the piston rod, is caused to move rearward by the pressure of gas against the face of the piston, the upper cam surface 29 will contact with the cylindrical pin thus forcing the locking arms or bars 53 downward to a point below the locking shoulders 46 of the breech-bolt, 30 thereby unlocking the breech bolt so that it can be forced to its rearward position by the shoulder 32' on the action slide which contacts with the depending lug 40 of the breech-bolt and carries it to the rear as soon as it is unlocked.

It will be understood that the locking arms or bars 53 are retained by a vertical recess or groove formed in each side of the inner walls of the receiver in order to prevent the action slide from carrying back the said locking bars 53.

When the action slide and breech-bolt reach the rear position, as shown in Fig. 1, the trigger is moved by the trigger spring 45 55 into engagement with the retaining notch or recess 30, and the parts are thus held in position until the trigger is pulled. When the trigger is pulled out of the retaining notch, the piston spring 24 forces the action 50 slide forward, and as the action slide pawl 34, has been forced upward by the pawl-spring 37, into engagement with the rear end of the depending lug 40, of the breech bolt, the breech bolt is thus carried 55 forward with the action slide to its forward position stopping against the rear end of the gun-barrel. During the forward motion of the action slide 25 the projecting cam surface 36' formed on the pawl comes in contact with the rounded corner 38' of the solid metal 38 and is forced down and out of engagement 60 with the breech-bolt, thereby allowing the action slide to continue its forward movement for the purpose of locking the bolt and 65 firing the cartridge, the locking of the breech

bolt being accomplished by the contact of the lower cam surface 29' with the cylindrical pin 52 which forces the pin and locking arms or bars 53 upward thereby forcing said locking arms or bars into the locked position behind the shoulders 46 of the breech-bolt, and the still farther forward movement of the slide causing its upward extending lug 27 to strike the rear end of the firing pin with sufficient force to drive the front 70 end of the firing pin into the primer and thus fire the cartridge, after which the gun will continue to fire as often as the trigger is pulled, or held back, and the cartridges are provided.

It will be understood that the locking arms or bars must be up in the locked position before the slide can come far enough forward to strike the firing pin, this feature preventing the discharge of the gun until the breech-bolt is securely locked and assumes its proper firing position.

The cartridges are carried by and fed from a drum shaped magazine secured on a stud 57, screw threaded at its lower end 58, 90 whereby it is screwed into the gun frame or receiver, and the bottom 58' of the magazine is provided with a slot 59 through which the cartridges are fed down through the opening 60 in the top of the gun frame or 95 receiver. The cartridge-carrier consists of a rotating integral inner and outer ring joined together by the central ribs 61, the outer ring 62 having a series of inward integral extensions 63 which carry the heads of the 100 cartridges and the inner ring 64, provided with a series of outward integral ribs or extensions 65, adapted to carry the bullet end of the cartridges. A convolute spring 66, of the general type used in clocks, is provided to rotate the cartridge carrier, and as the cartridges are rotated past the slot 59 the projecting portion 67 integral with the bottom plate 58', serves to guide the cartridges down through the slot and into the 110 receiver from which they are then pushed into the barrel during the forward movement of the breech-bolt.

By reference to the drawings it will be seen that the ejector 49 prevents more than one cartridge at a time getting in front of the breech-bolt when the bolt is in its rear position, and the top of the bolt itself serves to stop the cartridge leaving the magazine when the bolt is in the forward position. 120 The magazine is also provided with a latch 68; a latch spring 69, and a pivot pin 70, carried by and secured to the sleeve 71, the said sleeve being formed integral with the bottom plate 58'. The latch 68 is adapted to 125 engage at one end with a series of ratchet teeth 72 forming a part of the rotating cartridge carrier, and when said latch is in engagement with the ratchet teeth prevents the rotation of said carrier and the escape- 130

ment of cartridges from the magazine when the latter is lifted off the stud 57 for reloading or other purposes.

As shown in Fig. 4, it will be seen that the 5 stud 57, is formed with a shouldered portion 78, which serves to raise the rear end of the latch 68 against the latch spring 69, thus automatically throwing the forward end of the latch out of engagement with the 10 ratchet teeth 72 on the cartridge carrier and thus permitting the magazine spring 66 to rotate the carrier whenever the magazine is seated all the way down on the stud as shown in Figs. 1, 2 and 4. The top 74 of the 15 magazine is readily removed in order to fill the magazine with cartridges by unscrewing it from the threaded upper portion 75 of the sleeve 71.

The stud 57 is provided with a spring actuated plunger or catch 76 having a tapered rounded point 77 which engages with a corresponding groove formed in the inner peripheral portion of the sleeve 71, the function of said plunger or catch being to exert 25 sufficient pressure against the grooved surface of the sleeve to prevent the magazine from falling off the stud, although the magazine may be readily removed by an operator using enough physical force to 30 force back the rounded point of the spring plunger or catch as the magazine is slid up or down on the stud in removing or attaching it. The said stud 57 is also provided with a key 78, which engages with a 35 key slot formed in the magazine sleeve 71, thereby preventing the sleeve from turning on the stud, since as one end of the magazine spring is secured to the non-revolving sleeve at 79, and the other acting end of the 40 spring is secured at 80 to the cartridge carrier, it is evident that the carrier alone will revolve between the cover and bottom plate as the spring acts.

If desired, the inner ring 64 may be 45 omitted and in place the bullet ends of the cartridges contained in the magazine may be guided downward by a spiral auger shaped groove contained in a non-revolving central portion such as is commonly used in 50 drum type magazines.

The operation of the parts of my improved mechanism, starting in the fired position shown in Fig. 2, is as follows:—

As soon as the bullet passes the gas outlet port hole in the gun-barrel a portion of the live powder gas rushes through said port hole, through the outlet port in the ring 7 and against the forward face of the piston 19, forcing the piston rearward against the 55 tension of the helical spring until the piston passes to the rear of the gas exhaust port or outlet 23 formed in the tube 20, the gas thus escaping through said exhaust port and the piston is then returned to its original forward position by the action of the helical 60

spring 24 which was compressed during the rearward movement of the piston. This action and construction is of the general nature used in many gas operated machine guns.

During the rearward movement of the piston, the action slide 25 secured to the piston rod, as shown, is carried rearward and the rearward movement of the action slide is used to unlock the breech-bolt 39 75 and move it to its rearward position as shown in Fig. 1. As the slide moves rearwardly, the upper cam surface formed in the slide engages with the cylindrical pin carrying the upright locking bars or arms 80 and said cam surface forces the said pin and locking bars downward until they are below the locking shoulders formed on the breech-bolt 39, thereby unlocking the breech bolt so that it can be forced to its rearward 85 position by the shoulder on the action slide which then comes into contact with the breech-bolt at the lower end of its depending lug and carries it to the rear as soon as it is unlocked.

When the action slide and breech-bolt reach the rear position shown in Fig. 1, the trigger is moved by the trigger-spring into engagement with the retaining notch or recess formed in the bottom of the action 90 slide and the parts are thus held in this position until the trigger is pulled. During the rearward motion of the breech-bolt the empty shell is extracted from the gun-barrel by means of the extractor hook pivoted 100 to the forward end of the breech bolt, and actuated by the helical spring in the usual manner as shown in Fig. 6.

The ejection of the fired shell is accomplished by the ejector pivoted to the receiver 105 or frame and is operated by the shoulder formed by a groove cut in the side of the breech-bolt, which shoulder strikes the rear end of the ejector during the last part of the rearward movement of the breech-bolt and thus throws the forward end portion of the ejector against the side of the fired shell with sufficient force to eject it out of the gun through the ejection slot formed in the side of the receiver. The ejector remains in 110 this position as the next loaded shell is fed down from the magazine and thus serves as a rest or platform for the loaded cartridge to rest upon and preventing it from rolling out the ejector slot until the breech-bolt starts to move forward when the front of the bolt will push the ejector back out of the path of the breech-bolt.

It is important to note that before the ejector is pushed out of the forward path 125 of the bolt the point of the bullet of the cartridge resting on the ejector will have started to enter the chamber being pushed thereby by the forward motion of the breech-bolt and thus prevented from falling out 130

of the ejection slot after the ejector is pushed from under it. The ejector thus serves as a gate for the magazine and guide for the loaded shell, in addition to its usual function of ejecting the empty shell. When the trigger is pulled out of the retaining notch, the piston spring forces the action slide forward and as the sear carried by said slide has been forced up by the sear-spring 10 into engagement with the rear end of the depending lug of the breech-bolt, the breech-bolt is carried forward with the action slide to its original forward position stopping against the rear end of the barrel. 15 During this forward motion of the slide the projecting cam surface on the spring actuated pawl comes in contact with the rounded corner of the solid metal within the gun frame or receiver and forces the pawl down 20 and out of engagement with the breech-bolt, thus allowing the action slide to continue its forward movement for the purpose of locking the bolt and firing the cartridge, the locking of the breech-bolt being accomplished by the action of the lower cam surface in the slide against the cylindrical pin carrying the upright locking arms or bars which forces the said locking arms or bars upward and into the locked position behind 25 the shoulders of the breech-bolt, and the still farther forward movement of the slide causing its upward extending lug to strike the rear projecting end portion of the firing pin with sufficient force to drive the front end 30 of the firing pin into the primer and thus fire the cartridge, after which the gun will continue to fire as often as the trigger is pulled, or as long as the trigger is held back and the cartridges are provided.

40 It is obvious that the cylindrical pin and locking arms, used for locking the breech bolt, may be made separate or integral.

Having thus described my invention, what I claim and desire to secure by Letters 45 Patent is:—

1. In a gun, the gun-barrel air cooling means comprising two cylindrical casings, two sleeves surrounding said barrel within said casings, each sleeve having a series of 50 integral longitudinal ribs radiating therefrom, and a ring secured to the barrel intermediate its length for connecting one end of each sleeve and one end of each of said casings.

55 2. In a gun, the gun-barrel air cooling means comprising two cylindrical casings, two sleeves surrounding said barrel within said casings, each sleeve having a series of integral longitudinal ribs radiating therefrom, and a ring secured to the barrel intermediate its length for connecting one end of each sleeve and one end of each of said casings, said ring being provided with a 60 gas outlet port registering with the outlet port in the gun-barrel.

3. In a gun, the gun-barrel air cooling means comprising two cylindrical casings surrounding the barrel, two sleeves within said casings and surrounding the barrel, each sleeve having a series of integral longitudinal ribs radiating therefrom, a ring secured to the barrel intermediate its length for connecting one end of each sleeve and one end of each of said casings, said ring having a vertical and a longitudinal gas outlet port registering with the outlet port in the gun-barrel, and means for regulating the outlet of gas from the ports in said ring. 70

4. In a gun, the gun-barrel air cooling means, the gun-barrel provided with a gas outlet port, a ring secured to said barrel provided with semi-circular openings therethrough at the sides of the gun-barrel for the passage of air, a vertical and a longitudinal gas outlet port formed therein and registering with the outlet in the barrel, means carried by said ring for regulating the outlet of gas from the said ports, and for supporting one end of a tube arranged below said gun-barrel. 80

5. In a gun, the gun-barrel air cooling means, the gun-barrel provided with a gas outlet port, a ring secured to said barrel intermediate the length of the barrel and intermediate said air cooling means having gas outlet ports formed therein adapted to register with the gas outlet in the gun-barrel, and formed with openings therethrough at the sides of the gun-barrel, means carried by said ring for regulating the outlet of gas from said ports, and for supporting one end of a tube arranged below said gun-barrel, and a gun sight mounted at the upper end of said ring. 95

6. In a gun, the gun-barrel air cooling means comprising two sections of cylindrical casings surrounding said barrel, a ring secured to the barrel intermediate its length, the rear end of the rear casing being connected to the gun frame and its front end to said ring, and the rear end of the front casing being secured to said ring, two sections of sleeves, each section having a series of integral longitudinal ribs radiating therefrom and surrounding the gun-barrel within said casings, the rear end of the rear sleeve fitted to the gun frame and the front end to said ring, and the front section of sleeve screwed to the outer end of the barrel and connected with said ring. 110

7. In a gas operated gun, a reciprocating action slide, a non-rotating reciprocating breech bolt, means carried by said action slide adapted to reciprocate said bolt, an actuating formation within said slide, and means carried and operated by the formation within said slide for locking and unlocking said bolt. 115

8. In a gas operated gun, a reciprocating action slide, a non-rotating breech bolt car- 120

rying a firing pin, means carried by said action slide for reciprocating said breech-bolt, means for locking and unlocking said bolt carried by the slide, and means formed 5 within said slide for operating said locking and unlocking means.

9. In a gas operated gun, a reciprocating action slide, a reciprocating breech-bolt having a depending rear end portion, means 10 carried by said slide to engage the rear face of said depending end adapted to move the bolt forward, means forming a part of said slide adapted to engage the front face of said depending end to move the bolt 15 rearward, an actuating formation within said slide, and means carried and operated by the formation within said slide for locking and unlocking the said breech-bolt.

10. In a gas operated gun, a reciprocating 20 action slide, a reciprocating breech bolt provided with locking shoulders, means carried by said action slide for reciprocating the breech-bolt, and upright bars carried and operated by said slide and adapted 25 to engage and disengage said locking shoulders for locking and unlocking the breech-bolt.

11. In a gas operated gun, a reciprocating action slide, a reciprocating breech bolt 30 provided with locking shoulders and a depending rear end portion, means carried by the slide for engaging the rear face of said depending end to move the bolt forward, means formed on the slide adapted to engage the rear face of the depending end to move the bolt rearward and upright bars carried and operated by the slide, said bars being lifted to engage said locking shoulders and lowered to disengage the shoulders 35 for locking and unlocking the said bolt.

12. In a gas operated gun, a reciprocating action slide, a reciprocating breech-bolt having a depending portion, a spring actuated returning pawl pivoted within a recess intermediate the length of said slide, said pawl serving to engage with and return the breech-bolt during the forward movement of the action slide.

13. In a gas operated gun, a reciprocating 50 action slide, a non-rotating reciprocating breech-bolt, and an integral upward extension formed on the slide adapted to strike the outer end of the firing pin to discharge a cartridge, an actuating formation within said slide, and means carried and operated by the formation within the action slide for locking and unlocking said breech-bolt.

14. In a gas operated gun, a reciprocating 60 action slide, a reciprocating breech-bolt provided with a centrally positioned firing pin, means carried by the slide for reciprocating said breech-bolt, means for locking

and unlocking the breech-bolt carried by said slide, and an upper and lower cam surface formed on said slide for raising said locking means to the locking position and lowering said means to the unlocked position by the movement of the slide.

15. In a gas operated gun, a reciprocating action slide, a reciprocating breech bolt, means carried by the slide for reciprocating the breech-bolt, and means for locking and unlocking said bolt, consisting of a cylindrical pin fitted in a longitudinal slot passing transversely through the said slide, and carrying an upwardly extended locking bar at each end of said pin, and an upper and lower cam surface formed within said slide adapted to elevate and depress said bars into the locked and unlocked position.

16. In a gas operated gun, a reciprocating action slide, a reciprocating breech-bolt, an ejector pivoted to the gun frame operated by the breech-bolt to eject the empty shell, said ejector being so positioned as to serve as a stop to prevent loaded cartridges from falling out the ejecting slot in the frame and to act as a gate for the magazine, an actuating formation within said slide, 90 and means carried and operated by the formation within the action slide for locking and unlocking said breech-bolt.

17. In a gas operated gun, a reciprocating action slide, a reciprocating breech-bolt, provided with a longitudinal groove formed in one side thereof terminating in a shoulder formed at its forward end, an ejector pivoted to the gun frame having a rear extension and a forward inclined extension, 100 and so positioned that it is operated by the breech-bolt to eject the empty shell and serves as a stop to prevent loaded cartridges from falling through the ejecting slot in the frame and as a gate for the magazine, 105 an actuating formation within said slide, and means carried and operated by the formation within the action slide for locking and unlocking said breech-bolt.

18. In a gas operated gun, a reciprocating action slide, a reciprocating breech bolt, means carried by the slide for reciprocating the breech-bolt, means carried and operated by said slide for locking and unlocking the breech bolt, a cartridge magazine secured to the gun frame by a rigid stud, an ejector pivoted to the gun frame and operated by the breech bolt to eject the empty shell, and serving as a stop for the loaded cartridge and a gate for the magazine, 115 an actuating formation within said slide, and means carried and operated by the formation within the action slide for locking and unlocking said breech-bolt.

ANSLEY H. FOX.
